J. L. COYLE

EGG BOX FILLER

Filed July 7, 1921

UNITED STATES PATENT OFFICE.

JOSEPH L. COYLE, OF VENICE, CALIFORNIA, ASSIGNOR TO JOHN H. THOMAS, OF LOS ANGELES, CALIFORNIA, AND ROY STANLEY DAVIS, OF VANCOUVER, BRITISH COLUMBIA, CANADA.

EGG-BOX FILLER.

Application filed July 7, 1921. Serial No. 482,945.

To all whom it may concern:

Be it known that I, JOSEPH L. COYLE, a subject of the King of England, residing at Venice, in the county of Los Angeles and 5 State of California, have invented new and useful Improvements in Egg-Box Fillers, of which the following is a specification.

This invention relates to crate and box fillers, and more particularly to fillers for 10 egg crates, although the features and advantages thereof are equally pertinent to fillers for fruit, vegetable and other crates and boxes. The invention has for its object to provide an improved filler of the 15 character mentioned which will be superior in point of relative simplicity and inexpensiveness of construction and assembling, facility in installation and packing and use, durability and stability and resistance to 20 crushing, strains and impact, and reliability in service, and which will be generally superior in efficiency, effectiveness and serviceability.

With the above and other objects in view, 25 the invention consists in the novel and useful provision, formation, combination, association, relative arrangement, mode of assembling and method of use and inter-relation of parts, members and features, all as 30 hereinafter described, shown in the drawing, and finally pointed out in claims.

In the drawing:

Figure 1 is a perspective view of a portion 35 of an egg crate, the same being broken away at one corner portion to disclose the invention in one embodiment;

Figure 2 is an enlarged fragmentary view of one form of the invention, showing the main and transverse partitions of a 40 filler assembled together, with a flat or spacer, in accordance with the invention;

Figure 3 is a view similar to Figure 2, taken along a line of vision at right angles to that of Figure 2;

Figure 4 is a fragmentary plan view of a 45 flat to be used in conjunction with the form of construction shown in Figure 5; and,

Figure 5 is a view similar to Figure 1 of a modified form of construction in conjunction with which the flat shown in Figure 4 is employed.

Corresponding parts in all the figures are designated by the same reference characters.

Referring with particularity to the drawing, A in Figures 2 and 3 thereof designates 55 in each instance one of a series of main partitions, and B designates similarly one of a series of transverse partitions of a filler embodying my invention, reference being had now to Figures 1, 2 and 3; and C designates a flat or spacer utilized in conjunction with the assembled series of fillers, such flats or spacers being disposed between adjacent superposed fillers. In Figures 4 and 5 D designates one of a series of main partitions, and E designates in each instance 60 one of a series of transverse partitions, such main and transverse partitions being associated and assembled together to constitute a modified form of filler embodying the invention, F designating a flat used in conjunction with said modified form of construction to be disposed between adjacent 65 or superposed fillers.

Referring now to Figures 1 to 3 inclusive, 75 the main partitions A comprise lengths or strips 6 of card board or other suitable material which are punched through at definite intervals to produce slots 7 having each an arcuate wall 8 and an opposite wall 9 which 80 may be straight or otherwise, said walls being joined by lateral off-set slots 10 ranging to the side of the edge 9 opposite to the wall 8. The slots 7 are disposed transversely of the strips 6, and their major axes 85 are preferably slightly inclined with respect to transverse planes of the strips 6. The members or partitions B consist of similar flat strips or lengths 11, of card board or other suitable material, which are notched at 90 predetermined intervals, related directly to the relative spacing of the partitions A, as at 12, to produce flaps 11^a substantially to the bottoms of the slots 10. The notches or slots 12 are opposed, in pairs, and are cut 95 to such depths that when they are inter-engaged with the partitions A at the ends of the slots 7, the partitions B will be bowed or beveled into arcuate form, as clearly shown in Figures 1 and 2, and so 100 maintained. Where the material of the partitions 6 is punched through to produce the slots 7, flaps 13 are formed at the straight edges 9 of such slots 7, and the same are projected into the cells or compartments which are produced when the 105

partitions A and B are assembled, the partitions A being spaced apart substantially in accordance with the spacing apart of the partitions B, so that substantially square cells are produced, although this may be widely varied in practice.

A convenient method of assembling the partitions A and B is by the use of a suitable punching device which cuts the slots 7 and communicating slots 10, and follows through to bend the respective flap 13 into its angular relation with the respective partition A; and this punch may continue on through the whole series of partitions A, forming the slots 7 and 10 consecutively, bending the flaps 13 consecutively, and carrying the respective partition B on through the successive slots 7 with the flaps 11^a bent into position to pass through the slots 10, and so held, until the partition B is completely introduced, whereupon the flaps 11^a may be bent upwardly and downwardly at the top and bottom of the partition B, and such partition B interlocked with the series of partitions A, the notches or slots 12 receiving the respective partitions A within themselves, as clearly shown in Figures 2 and 3.

The fillers are then completely assembled, and may be installed in superposed relation, as shown in Figure 1, with the flats C alternating with the fillers, and the cells bounded by the partitions A and B may be filled with eggs, fruit, vegetables or other objects against which the flaps 13 will respectively bear, yieldingly, to assist in firmly holding the objects in the cells, and oppose any shaking or rattling or displacement thereof. The top walls of the slots or openings 7 and the top portions of the walls 9 of such slots in conjunction with the top portions of the walls 8 thereof, will confine the partitions B in bowed form, under compression, and prevent their displacement either lengthwise of the slots or openings 7, or in directions angularly related thereto. This bowed condition of the partitions B will assist in holding the said partitions B firmly in place and add stability to the entire assembled form, because of the compressive action of such bowed fillers B, due to the natural inherent spring quality thereof; and such spring quality of the partitions B will likewise assist in firmly holding the objects in the cells, yieldingly opposing any rattling, shaking, jar or displacement thereof. When the fillers are all assembled together in superposed relation with the flats C alternating therewith, and the objects in their places, they may be confined within the egg box or crate G, as shown in Figure 1.

The form of construction shown in Figures 4 and 5 is the same in all respects as that above described and shown in the drawing, with the exception that the partitions

D are formed of blanks, strips or lengths 13 having hill-and-valley edge portions 13^a, at each edge, with the hills at one edge opposed to the valleys at the other edge; and the flats F are corrugated, and provided in the angular portions thereof with slots 13^b extending lengthwise of the flat and at both sides of and in series between the sides of the flat, so as to register with and receive the hill-and-valley portions 13^a of the blanks or strips 13, such hill-and-valley portions terminating in curved edged junction zones, as at 13^c; thus interlocking the flats with the partitions D or the blanks 13 thereof, and spacing apart superposed fillers, for ventilation or prevention of dangerous or destructive thrust of the object in the filler cells, such thrusts otherwise tending to cause breakage of the contents of the cells, and being imparted from cell to cell through the flats or spacers between the fillers. This objectionable end thrust is largely eliminated in the form shown in Figures 1 to 3 inclusive, and particularly in the packing and storing of eggs, and other frangible objects, due to the inclination of the partitions B, which tend to incline the longitudinal axes of the eggs or other objects, as clearly shown in Figures 1 to 3 inclusive, and thus bring the end portions of the objects out of direct opposition. Of course any such end thrust is likewise opposed by the flats between the fillers.

The form of construction shown in Figures 4 and 5 may be assembled in the same manner as that shown in the other Figures, and the partitions E may be formed the same as the blank 11 of the partition B, and the same advantages will inhere in the use of the modified form in Figures 4 and 5 as flow from the use of the other form.

The openings or slots 7 serve to effectively aerate or ventilate the cells and the objects therein, or to maintain the same at proper temperature.

The fillers may be readily assembled and folded into compact form when assembled without separating the partitions, and are durable and effectively resist strain, jar, impact, and other mechanical attack, and when used in conjunction with the flats constitute a highly efficient and reliable means for transporting eggs, or other perishable or frangible or readily damaged objects or commodities, and the fillers, either with or without the flats, may be effectively depended upon for long periods of successful storage or shipment, the flats being used where the commodities require same.

The arcuate walls 8 of the slots 7 provides a sufficient width for the slots so that the traverse partitions B and E may be passed through said slots in a much more bowed form than finally assumed, so that the flaps 11^a may be passed through the slots 10 with-

out too abruptly bending said flaps with relation to the main bodies of the partitions of which they are a part.

It is obvious that many changes may be made in practicing the invention, with modifications and variations of various kinds, all with respect to and in departure from the construction and inter-relation and mode of use of the parts, members and features, shown in the drawing and hereinabove set forth, and without departing from the real spirit of the invention.

Having thus disclosed my invention, I claim and desire to secure by Letters Patent:

15 1. A filler of the character disclosed, comprising main and transverse partitions, the main partitions having openings through which the transverse partitions are passed to assemble the filler; said transverse partitions being of a material having an inherent spring quality and being confined within said openings in bowed form in which they are maintained by said spring quality and the walls of such openings; said openings 25 being enlarged to permit the passage of said transverse partitions therethrough in bowed form.

2. A filler of the character disclosed, comprising main and transverse partitions, the main partitions having openings through which the transverse partitions are passed to assemble the filler; said transverse partitions being of a material having an inherent spring quality and being confined within said openings in bowed form in which they are maintained by said spring quality and the walls of such openings; said openings being enlarged to permit the passage of said transverse partitions therethrough in bowed 40 form and having each an arcuate wall.

3. A filler of the character disclosed, comprising main and transverse partitions, the main partitions having openings through which the transverse partitions are passed to assemble the filler; said transverse partitions being of a material having an inherent spring quality and being confined within said openings in bowed form in which they are maintained by said spring quality and the walls of such openings; said openings being enlarged to permit the passage of said transverse partitions therethrough in bowed form and having each an arcuate wall; said openings being provided with off-set slots through which edge portions of said transverse partitions may be passed.

4. A filler of the character disclosed, comprising main and transverse partitions, the main partitions having openings through which the transverse partitions are passed to assemble the filler; said transverse partitions being of a material having an inherent spring quality and being confined within said openings in bowed form in which they are maintained by said spring quality and

the walls of such openings; said openings being enlarged to permit the passage of said transverse partitions therethrough in bowed form and having each an arcuate wall; said openings being provided with off-set slots 70 through which edge portions of said transverse partitions may be passed, and said last mentioned edge portions being slotted to receive the edge portions of the main partitions when said transverse partitions are 75 in final positions.

5. A filler of the character disclosed, comprising main and transverse partitions, the main partitions having openings through which the transverse partitions are passed 80 to assemble the filler; said transverse partitions being of a material having an inherent spring quality and being confined within said openings in bowed form in which they are maintained by said spring 85 quality and the walls of such openings; said openings being enlarged to permit the passage of said transverse partitions therethrough in bowed form; flaps being provided on said main partitions at margins of 90 said openings and extending into the cells of the assembled partitions.

6. A filler of the character disclosed, comprising main and transverse partitions, the main partitions having openings through 95 which the transverse partitions are passed to assemble the filler; said transverse partitions being of a material having an inherent spring quality and being confined within said openings in bowed form in which they are maintained by said spring quality and the walls of such openings; said openings being enlarged to permit the passage of said transverse partitions therethrough in bowed 100 form; flaps being provided on said main partitions at margins of said openings and extending into the cells of the assembled partitions; said flaps serving as yielding members for contact with objects in said cells.

7. A filler of the character disclosed, comprising main and transverse partitions, the main partitions having openings through which the transverse partitions are passed to assemble the filler; said transverse partitions being of a material having an inherent spring quality and being confined within said openings in bowed form in which they are maintained by said spring quality and the walls of such openings; said openings being enlarged to permit the passage of said transverse partitions therethrough in bowed form; in combination with flats for disposition in alternation with assembled fillers.

8. A filler of the character disclosed, comprising main and transverse partitions, the main partitions having openings through which the transverse partitions are passed to assemble the filler; said transverse parti- 130

4
tions being of a material having an inherent spring quality and being confined within said openings in bowed form in which they are maintained by said spring quality and 5 the walls of such openings; said openings being enlarged to permit the passage of said transverse partitions therethrough in bowed form; in combination with flats for disposition in alternation with assembled fillers; 10 said main partitions being provided with edge projections, and said flats being notched to receive the same.

9. A filler of the character disclosed, comprising main and transverse partitions, the 15 main partitions having openings through which the transverse partitions are passed to assemble the filler; said transverse partitions being of a material having an inherent spring quality and being confined within 20 said openings in bowed form in which they are maintained by said spring quality and the walls of such openings; said openings being enlarged to permit the passage of said transverse partitions therethrough in bowed 25 form; in combination with flats for disposition in alternation with assembled fillers; said main partitions being provided with edge projections, and said flats being notched 30 to receive the same; such edge projections being in hill-and-valley relation at each edge of each main partition.

10. A filler of the character disclosed, comprising main and transverse partitions, the main partitions having openings through 35 which the transverse partitions are passed to assemble the filler; said transverse partitions being of a material having an inherent spring quality and being confined within said opening in bowed form in which they are maintained by said spring quality and 40 the walls of such openings; said openings being enlarged to permit the passage of said transverse partitions therethrough in bowed form; in combination with flats for disposition in alternation with assembled fillers; 45 said main partitions being provided with edge projections, and said flats being notched to receive the same; such edge projections being in hill-and-valley relation at each edge 50 of each main partition; the hills at one edge being in opposed relation to the valleys at the other edge.

11. A filler of the character disclosed, comprising a series of main partitions provided with openings, and a series of trans- 55 verse partitions passed through said openings, said openings having major axes inclined to perpendicular transverse planes of said main partitions.

12. A filler of the character disclosed, comprising a series of main partitions having openings, a series of transverse parti- 60 tions passed through said openings and having major axes extending cross-wise of said main partitions; said transverse partitions

being of flexible material and being confined within said openings in bowed form.

13. A filler of the character disclosed, comprising a series of main partitions having openings, a series of transverse parti- 70 tions passed through said openings and having major axes extending cross-wise of said main partitions; said transverse partitions being of flexible material and being confined within said openings in bowed form; means 75 being provided for preventing displacement of said transverse partitions.

14. A filler of the character disclosed, comprising a series of main partitions having openings, a series of transverse partitions 80 passed through said openings and having major axes extending cross-wise of said main partitions; said transverse partitions being of flexible material and being confined within said openings in bowed form; means 85 being provided for preventing displacement of said transverse partitions both transversely and lengthwise of said main partitions.

15. A filler of the character disclosed, comprising a series of main partitions having openings, a series of transverse partitions 90 passed through said openings and having major axes extending cross-wise of said main partitions; said transverse partitions being of flexible material and being confined 95 within said openings in bowed form; means being provided for preventing displacement of said transverse partitions both transversely and lengthwise of said main partitions; said transverse partitions having each 100 an inherent spring quality.

16. A filler of the character disclosed, comprising a series of main partitions having openings, a series of transverse partitions 105 passed through said openings and having major axes extending cross-wise of said main partitions; said transverse partitions being of flexible material and being confined within said openings in bowed form; means being provided for preventing displacement 110 of said transverse partitions both transversely and lengthwise of said main partitions; said openings having lateral off-set slots through which edge portions of said transverse partitions may be passed in assembling the partitions; and said trans- 115 verse partitions being notched to receive edge portions of said main partitions when the partitions are assembled and preventing displacement thereof in one direction.

17. A filler of the character disclosed, comprising a series of main partitions and a series of transverse partitions assembled therewith, certain of said partitions having edge projections; and corrugated flats 120 slotted to receive said edge projections.

18. A filler of the character disclosed, comprising a series of main partitions and a series of transverse partitions assembled therewith, certain of said partitions having 125

edge projections; and flats notched to receive said edge projections; said flats being corrugated and having the notches in the angular portions thereof.

5 19. A filler of the character disclosed, comprising a series of main partitions having through openings and a series of transverse partitions assembled therewith and extending through said openings; there being flaps provided in the main partitions at

the margins of said openings and which flaps project into the spaces bounded by the partitions.

In testimony whereof, I have signed my name to this specification in the presence of 15 two subscribing witnesses.

JOSEPH L. COYLE.
